UNITED STATES PATENT OFFICE

141,671

DESIGN FOR A CHAIR

Carlton J. Bannister, Overbrook Hills, Pa., assignor to Bunting Glider Company, Philadelphia, Pa., a corporation of Pennsylvania

Application February 26, 1945, Serial No. 118,136

Term of patent 7 years

(Cl. D15—1)

To all whom it may concern:

Be it known that I, Carlton J. Bannister, a citizen of the United States and a resident of Overbrook Hills in Merion, county of Montgomery, State of Pennsylvania, have invented a new, original, and ornamental Design for Chair, of which the following is a specification, reference being had to the accompanying drawing, forming a part thereof, wherein:

Figure 1 is a perspective view of a chair, showing my new design; and

Figure 2 is a side elevational view thereof.

The dominant features of my design reside in the parts shown in solid lines.

I claim:

The ornamental design for a chair, as shown and described.

CARLTON J. BANNISTER.
